ROUND PADDLE BOAT

Carl Roberts, 6669 Charing St.,
Santa Susana, Calif. 93063

Filed July 19, 1973, Ser. No. 380,766

Term of patent 3½ years

Int. Cl. D12—06

U.S. Cl. D12—68

Fig. 1

Fig. 3

Fig. 2

Fig. 4

Fig. 5

FIG. 1 is a perspective view of my invention basically illustrating the front and left side thereof with a seat and paddle crank on the upper portion of the hull;

FIG. 2 is a front view of the round paddle boat of my invention illustrating paddles projecting from the bottom of the boat's hull at oblique angles;

FIG. 3 is a top view of the round paddle boat invention shown in FIG. 1, illustrating the paddle cranks on the upper portion of the hull;

FIG. 4 is a bottom view of the round paddle boat invention shown in FIG. 1; and

FIG. 5 is a right side view of the round paddle boat of my invention taken 90° from the view shown in FIG. 2.

I claim:

The ornamental design for a round paddle boat, as described and shown.
